United States Patent

Des. 235,955
Patented July 22, 1975

235,955

COUNTER TOP

Joseph P. Shelley, Jr., 614 Webster Ave.,
New Rochelle, N.Y. 10801

Filed Jan. 24, 1972, Ser. No. 220,553

Term of patent 14 years

Int. Cl. D6—06

U.S. Cl. D6—191

FIG. 1

FIG. 2

FIG. 3

FIG. 4

FIG. 1 is a perspective view of a counter top showing my design;

FIG. 2 is a view in end elevation, the end not shown being a mirror image of the side shown;

FIG. 3 is a vertical section of the counter top of FIG. 1, taken along the line 3—3 of FIG. 4, and

FIG. 4 is a top plan view thereof.

I claim:

The ornamental design for a counter top, as shown and described.
